UNITED STATES PATENT OFFICE.

WILLIAM WELLS COLLYER, OF STOCKPORT, ENGLAND, ASSIGNOR TO THE HAT MANUFACTURERS SUPPLY COMPANY, LIMITED, OF STOCKPORT, ENGLAND.

SWEATBAND FOR HATS.

Application filed September 17, 1921. Serial No. 501,330.

To all whom it may concern:

Be it known that I, WILLIAM WELLS COLLYER, a British subject, residing at Stockport, county of Chester, England, have invented certain new and useful Improvements in Sweatbands for Hats, of which the following is a specification.

This invention relates to sweat bands for hats in which an elastic or other cord is carried in a fabric formed into a loop or hem and stitched to the leather and a tape with an openwork or perforated edge is also stitched to the leather.

As hitherto constructed the openwork tape has been formed by weaving or "hemstitching" apart from the leather, a second piece of fabric has been cut and folded into a loop or hem to receive the cord and the parts have been stitched on to the leather.

This invention is designed to eliminate the separate operation of perforating the tape and to utilize one piece of tape or material to form the cord receiving loop or hem and also the openwork or perforated edge.

It consists in employing a single piece of tape or fabric woven or folded into a loop or hem and stitching both edges to the hat leather, one or both projecting beyond the edge of the leather and at the same operation perforating the projecting edge or edges in a hemstitching machine, one set of stitches forming the double function of binding one side of the hemstitch perforations, and stitching both edges of the tape or fabric to the leather.

The invention will be fully described with reference to the accompanying drawings.

Fig. 1. is a side view of part of leather with the combined perforated and looped fabric strip containing cord *a*.

Fig. 2. is a transverse section of same.

Fig. 3. is a side view drawn to an enlarged or exaggerated size.

Fig. 4. is a transverse section of Fig. 3.

The tape or fabric strip *A* is a plain piece of fabric preferably with a selvage woven along both edges and fewer warp threads along one edge, though it may be a strip of fabric cut from the piece, and the sweat band *B* is an ordinary plain band of leather or other material.

The tape or fabric *A* and the leather *B* are together fed into a hemstitch sewing

machine with a plunger and two needles which work in the usual way. The tape or fabric *A* as it passes into the machine with the leather *B* is folded into a loop or hem enclosing a cord *a'* of elastic or other material one or both edges of the fabric or tape *A* (preferably one edge only) projecting beyond the edge of the leather.

Instead of a plain tape or fabric folded over on itself to form the hem or loop, a tape or fabric may be woven double as a hem to receive the cord *a'*, the tape being fed or guided into the machine together with the leather, one edge projecting beyond the edge of the leather.

The hem stitch sewing machine works in the usual way, the plunger enters the projecting edge *a* or edges of the fabric *A* and forms the perforation therein, one needle makes the binding stitch on the outside edge of the fabric and the other needle passes through both the leather and the two ply of tape or fabric, thereby forming the hem or loop in the tape or fabric, the stitch performing the double function of binding the edge of the perforations and attaching the tape to the leather.

By this method of manufacture a sweat band is formed having an openwork or perforated tape and a loop or hem for an elastic or other cord along one edge at one operation, and a neater and more satisfactory finish is obtained.

What I claim as my invention and desire to protect by Letters Patent is:—

1. The method of manufacturing hat leathers or sweat bands having a perforated openwork tape along one edge and a looped fabric containing a cord which consists in feeding a plain strip of fabric, a leather band and cord, simultaneously into a sewing machine folding the fabric strip into a loop to enclose the cord as they are fed into the machine, and forming the openwork holes in the fabric by the same operation as it is stitched to the leather band, the binding stitches at one side of the perforations forming the double function of binding the perforations and stitching the fabric to the leather.

2. A hat leather or sweat band comprising in its construction a strip of leather and a strip of plain fabric having perforations formed along one edge, the other edge being

folded into a hem and hemstitches which bind the material on one side of the perforations and also penetrate the leather and secure the fabric thereto.

5 3. In a hat-leather or sweat band the combination with the leather of a strip of plain fabric folded into a hem and stitched thereto, a cord within the fold of the fabric and hem stitches penetrating the leather and

10 both edges of the fabric, attaching the two

together and forming openwork perforations in the edge of the fabric.

In testimony whereof I have hereunto set my hand in presence of two subscribing witnesses.

WILLIAM WELLS COLLYER.
